UNITED STATES PATENT OFFICE.

GEORGE E. PICKUP, OF NEWARK, OHIO, ASSIGNOR TO THE WEHRLE COMPANY, OF NEWARK, OHIO, A CORPORATION OF OHIO.

GAS HOT PLATE.

Application filed September 11, 1922. Serial No. 587,639.

To all whom it may concern:

Be it known that I, GEORGE E. PICKUP, a citizen of the United States, residing at Newark, in the county of Licking and State of Ohio, have invented a certain new and useful Gas Hot Plate, of which the following is a specification.

The invention relates to gas heating appliances of the type generally known as hot plates; and the object of the invention generally stated is to increase the efficiency of appliances of this character as well as to improve their appearance.

More specifically; the object of the invention is to produce a hot plate having enclosing side and bottom walls secured together in a simple and effective manner so as to form with a top plate a housing for the burners which serves to prevent waste of heat; renders the hot plate capable of use out-of-doors; and presents a neat and attractive appearance.

In the accompanying drawings I have illustrated but one form of my invention, but it is contemplated that various changes in the construction and arrangement of the parts may be made by those skilled in the art without departing from the spirit and scope of the invention as expressed in the pending claims.

Figure 1 of the drawings is a perspective view of a hot plate constructed in accordance with my invention.

Fig. 2 is a horizontal sectional view looking upwardly substantially in the plane of line 2—2 of Fig. 3.

Fig. 3 is a vertical sectional view taken in the plane of line 3—3 of Fig. 2.

Fig. 4 is a fragmentary sectional view showing a detail of construction, and taken in the planes of lines 4—4 of Fig. 2.

Fig. 5 is a horizontal sectional view taken in the plane of line 5—5 of Fig. 3.

My improved hot plate comprises generally a top frame or plate 7 in which are removable supported grids 8; a pair of end plates 9 rigidly secured upon the under side of the top plate at its opposite ends; front and rear plates 10 and 11 interposed between the end plates and inter-engaging therewith and with the top plate so as to be held firmly in their respective positions; and a bottom plate 12 constituting the drip-pan and removably supported between the end plates near the lower edges of the latter.

Below each of the grids 8 is supported a burner 13 upon a rod 14 which also depends for its support upon the end plates 9. A gas manifold 15 is carried by brackets 16 secured upon the underside of the top plate 7 forwardly thereof and is provided with valves 17 for controlling the flow of gas to the burners 13.

The construction is such that through the interengagement of the front and rear plates 10 with the top and end plates, said front and rear plates are firmly held in position. Consequently the use of bolts in fastening the several walls together is avoided except in securing the end plates to the top plate. 60 The bottom plate or drip-pan likewise is held in its normal position by interengagement with the end plates.

The top plate 7 is substantially rectangular in form having a depending flange 18 at its edges. Usually in appliances of this type two burners are provided, and herein I have shown my top-plate 7 as provided with two grid openings 19 in which are removably supported, the grids 8 of usual construction. Otherwise the top plate forms a closed upper wall for the burner chamber or housing.

The end plates 9 are rigidly secured at their upper edges to the underside of top plate 7 near the opposite ends thereof. The means for thus securing these parts together preferably comprise outwardly projecting bifurcated lugs 20 adapted to engage at their free ends the underside of the top plate 7 and to receive fastening bolts 21 entered through apertures in the top plate (Fig. 4). Upon the rear or inner side of the end plate is provided a pair of laterally projecting lugs 22, near the opposite edges of 75 said plate, adapted to engage with depending lugs 23 upon the under side of the top plate. The diverging portions of the bifurcated lugs engage with bosses 20a upon opposite sides of the bolts 21, and the construction is such that when the clamping bolts 21 are tightened a rigid connection between the end plates and the top plate is obtained.

Projections 24 formed upon the underside of the top plate are adapted also to engage in the bifurcated lugs 20 near their outer ends, and the lower ends of said projections depend a short distance beyond the lower surface of the lugs so as to provide shoulders with which the nuts of the clamping bolts 105 110

are arranged to engage and thus be held against turning. This facilitates the assembling of the parts since it renders it unnecessary to hold the nut by means of a tool 5 while the bolt is being turned.

The means thus provided for fastening the end plates to the top plate has been found to be exceedingly effectual, serving rigidly to hold the parts in proper relation.

10 The means for effecting the interengagement between the front and rear plates 10 and 11, the top plate 7, and the end plates 9, so as to hold said front and rear plates in position between the end plates, will now 15 be described,

20 Projecting from the underside of the top plate near the front and rear thereof is a series of lugs 25 for holding the front and rear plates 10 and 11 against lateral movement. The lugs 25 are staggered so that the alternate lugs bear against opposite sides of the front and rear plates when the latter are pressed against the top plate. The 25 vertical ends of each front plate 10 or rear plate 11 are wedged between an inwardly extending flange 26 on each end plate 9 and a curved shoulder 22^a formed on the outer side of the lug 22. It will be remembered that the lugs 22 project from the end plate 9 and assist in securing the latter to the top plate 7. Thus, in the present instance, the upper end and the vertical edges of the front and rear plates 10 and 11 are held between two opposed surfaces, an outer 30 surface formed by the flange 26 and the outermost lugs 25, and an inner surface formed by the innermost lugs 25 and the shoulder 22^a.

35 The lower edge of the front plate is supported in sockets 27 formed upon the inner sides of the end plates 9 as continuations of the flanges 26 (Fig. 3); and the lower edges of the rear plate 11 are supported upon horizontal ledges 28 and between vertical flanges 29 on said ledges and the flange 26, said ledges and flanges being formed upon the inner side of each of the plates 9. Preferably the front and rear plates are 40 constructed of sheet metal of relatively light 45 gauge, the lower edge of the front plate being beaded so as to enclose a reinforcing rod 10^a, and the lower edge of the rear plate being provided with an inturned flange 30 adapted 50 to engage in the socket provided by the ledges 28 and the flanges 26 and 29.

To receive the drip pan 12 the front plate 10 terminates a short distance above the lower edges of the end plates 9, and the latter are provided at a spaced interval 55 below the sockets 27 with horizontal ledges 31 forming supports upon which the drip pan may slide. The flange 29 at the rear edges of the plates 9 constitutes stops for limiting the rearward or inward movement 60 of the drip pan (Fig. 3). For supporting

the appliance in slightly elevated position, the end plates are provided with feet 32 formed integral therewith.

The gas burners 13 may be of any suitable or preferred construction, adapted to engage 70 with the supporting rod 14. The opposite ends of the latter are entered in sockets 33 formed upon the inner sides of the end plates a short distance below their centers.

75 The gas manifold 15 is in the form of a pipe closed at one end and open at its opposite end so as to be adapted for connection with a suitable source of gas supply. The brackets 16 for supporting this pipe may be of any preferred construction, being herein shown as formed of sheet metal and secured at their upper rear ends to the underside of the top plate near its forward edge. To this end each of said brackets is provided 80 near its rear end with a shoulder 34 adapted to engage with the lower edge of the forward flange 18 of the top plate, and the extreme rear end of the bracket is adapted to engage with a shouldered lug 35 depending from the top plate angularly of the front 85 wall 10, the latter being apertured in order thus to receive the end of the bracket. A bolt 36 is entered through the top plate and engages with the bracket 16 between the shoulder 34 and the lug 35, thus rigidly 90 clamping the bracket in position.

95 In order to receive the forward end portion of the burner 13, and also provide for the admission of air to the burner chamber, the front plate 10 is provided with apertures 37.

100 It will be observed that the construction which I have provided is extremely simple, enabling the construction of the parts at a relatively low cost as well as their rapid 105 assembling. By the provision of a chamber or housing for the burners, the efficiency of the appliance is increased through the concentration of the heat upon the cooking utensils supported upon the grids. Moreover, the enclosed chamber for the burners 110 renders it possible to use the hot plate out-of-doors where the ordinary construction is incapable of use because of excessive drafts. Finally, the appearance of the appliance is 115 improved by reason of the fact that the housing serves to conceal the unsightly burners from view.

118 I claim as my invention:

120 1. A hot plate comprising a rigid top frame provided with one or more grid openings, a pair of rigid end plates, means for detachably securing the end plates to the under side of the top plate at opposite ends of the latter, said end plates constituting supports for the top plate, and a rear plate 125 interposed between and interengaging with said end plates so as to be held in position by the end plates when the latter are secured to the top plate, said rear plate and 130

the two end plates coacting with the top plate to provide a burner chamber.

2. A hot plate comprising, in combination, a rigid top frame provided with one or more grid openings, a pair of rigid end frames bolted to the under side of the top frame at opposite ends thereof and constituting supports for the top frame, and front and rear plates interposed between said end frames beneath the top frame and interengaging with said frames so as to be held in position by the end frames when the latter are secured to the top frame.

3. A hot plate comprising, in combination, a rigid top frame provided with one or more grid openings, a pair of rigid end frames bolted to the under side of the top

frame at opposite ends thereof and constituting supports for the top frame, front and rear plates interposed between said end frames beneath the top frame and interengaging with said frames so as to be held in position by the end frames when the latter are secured to the top frame, and a drip pan supported at its opposite ends by said end frames for sliding movement in a front to rear direction, the front plate having its lower end terminating above said drip pan to permit such sliding movement of the latter.

In testimony whereof, I have hereunto affixed my signature.

GEORGE E. PICKUP.
